United States Patent Office.

SERENO GAYLORD, OF CHICOOPEE, MASSACHUSETTS.

Letters Patent No. 66,488, dated July 9, 1867.

IMPROVEMENT IN TRUNK-LOCKS.

The Schedule referred to in these Letters Patent and making part of the same.

TO ALL WHOM IT MAY CONCERN:

Be it known that I, SERENO GAYLORD, of Chicopee, Hampden county, Commonwealth of Massachusetts, have invented a new and improved Chest-Lock; and I do hereby declare that the following is a full and exact description thereof, reference being had to the accompanying drawings, and to the letters of reference marked thereon. In the drawings—

Figure 1 is an interior view of my lock.

Figures 2 and 3, sectional views of the mechanism of the same.

This invention consists of a lock more particularly adapted to chests, trunks, &c., so arranged that the mechanism inside may be arranged in a number of ways, requiring a different key for each new arrangement.

In construction I form my lock with two or more catches B B' A A' on each side of the key-pin a . These catches are hung on pins 1 1, a little below and on each side of the key-pin a . These catches rest upon and are guided by a piece, E, attached to the plate of the lock, and forming a stop-guide for the catches. This piece E projects at each end at $b b'$, and in the centre at c , being brought at these points to the same plane as that of the top of the catch, so that, when the back-plate or cover of the lock is put on, it rests against these projections, leaving the intervening spaces for the catches to work in. Attached to each of the catches A A' and B B' are steel springs $f f'$, which are fastened in a suitable manner to the lower and outer edges of the catches, and which press at their other ends against the projections $b b'$ on the ends of the piece E. By this arrangement they keep the catches pressed up against the middle projection c until forced back by the turning of the key. Beneath the lower ends of the catches A B, &c., are placed guards C and D. These are small plates, with curves on their upper edges, centring toward the key-pin, and serve the purpose of preventing the lock from being opened by the turning of a wrong key. These guards are slipped upon the pins 1 1, each guard having two holes in it for the purpose. These guides, when so placed, form rests for the lower ends of the catches, while the recesses in the piece E form rests at their bottom edges for the upper ends of the catches on the same plane.

By this means I obtain a lock which can be arranged in as many different ways as the combination and arrangements of the catches and guards can supply, and the catches are made of different widths and distances from the key-pin, so that a different key is required to open the lock each time it is arranged differently.

In figs. 2 and 3 is shown a section of the lock, with the catches and guards reversed, and on a line with them is shown the key required to fit each new arrangement. The projections $b b'$ upon the piece E form stops and guards also for the catches, so that a key which may fit in other respects cannot turn around inside the lock.

And now having described my invention, what I claim as new, and desire to secure by Letters Patent, is—

1. I claim, in a catch-lock, placing two or more catches A A' B B' on each side of the key-pin, and working on pins 1 1 at their lower ends, the distances between the key-pin and key-bearings being different on the upper and lower catches, so that, by reversing the same, a different lock may be formed, the parts arranged substantially as herein shown.

2. In combination with the above, the key-guards C and D, arranged substantially as and for the purpose shown.

SERENO GAYLORD.
